United States Patent Office

Des. 210,247

Patented Feb. 20, 1968

210,247

MUTE

Diane M. Olson and Robert D. Olson, both of
605 West Ave., Fullerton, Calif. 92632

Filed Aug. 1, 1966, Ser. No. 3,285

Term of patent 14 years

(Cl. D56—1)

FIG. 1 is a perspective view of the mute of our design;
FIG. 2 is a top plan view thereof;

FIG. 3 is a bottom plan view of the mute; and

FIG. 4 is a side elevational view in partial section
showing the concave depression in the bottom of the
mute.

We claim:

The ornamental design for a mute, as shown and
described.
